METHOD OF KNITTING STOCKINGS ON
FLAT KNITTING MACHINESWoldemar Heinitz, Chemnitz, Germany, assignor
to Schubert & Salzer Maschinenfabrik Aktien-
gesellschaft, Chemnitz, GermanyApplication August 1, 1931, Serial No. 554,550,
and in Germany August 19, 1930

4 Claims. (Cl. 66—187)

My invention relates to a method of knitting stockings in a single operation on flat knitting machines, and to the stockings obtained thereby.

My invention has particular reference to methods in which the heel and foot portions are knitted at the same time and selvedge loops to be seamed are widened outwardly for widening the heel portions.

It is an object of my invention to effect the rounding and narrowing of the heel subsequently to the widening of the heel in a novel manner. To this end I perform the several narrowing operations required for rounding and narrowing the heel in such manner that all drawbacks of other methods in which the heel portions are knitted simultaneously with the foot portions connecting them, are eliminated and a heel is obtained having a narrowing line similar to that of the pocket heels which could be knitted only on two machines heretofore, i. e., a narrowing line which extends substantially vertically toward the sole. The thread guide is moved back for various distances in accordance with the desired form of the narrowing line.

The novel heel obtained in accordance with my invention is particularly suitable as a substitute for the pocket heels which heretofore could be knitted only on separate machines, one machine for the leg, and another machine for the foot. Furthermore the heel possesses the particular advantage that it is in fact developed from the leg and is not, like the old heels, nothing but a partly straight extension of the leg which is thereupon merely shaped or stretched on a stocking mold.

In the drawings affixed to this specification and forming part thereof diagrams of loops and stockings knitted in accordance with my method are illustrated diagrammatically by way of example.

In the drawings

Figs. 1, 2 and 3 are diagrams of loops, and

Figs. 4, 5 and 6 are elevations showing part of the stockings obtained in accordance with such diagrams.

Referring now to the drawings, and first to Figs. 1 and 4, the leg is finished in the usual manner as far as the line $a-a$. In the next row of loops an edge loop is obtained at both sides by widening for one needle. In the following rows two edge loops are obtained by widening at opposite sides and so on, until the desired width of the heel is attained at $b-b$. From this point the heel is rounded by narrowing for one needle the heel loops but not the edge loops. The edge

loops remain and the width of the fabric is constant as far as the line $c-c$. For narrowing the heel all loops including the edge loops are narrowed for two needles from the row $c-c$, the tickler being moved back for two needles until at row $d-d$ only the number of loops required for the foot is left. Preferably, in order to obtain a good fit and edge loops which sew easily, plain, i. e., unarrowed, rows are inserted between the narrowed rows.

Referring now to Fig. 4, it will appear that the narrowing line B, C, D which extends substantially in vertical direction toward the sole, remains on the same weal throughout its length. This is obtained by moving the tickler back for the number of the narrowed loops. While the heel is rounded from $b-b$ to $c-c$ the tickler is moved back for one needle, and during the narrowing of the heel from $c-c$ to $d-d$ it is moved back for two needles.

Instead of two edge loops only one edge loop may be made.

Referring now to Figs. 2 and 5, the operation is the same as described with reference to Fig. 1, as far as the line $c-c$. The narrowing of the heel from $c-c$ to $e-e$ is effected in two stages, the tickler being moved back for two needles in the first half, as far as $d-d$, and for one needle only in the second half, from $d-d$ to $e-e$.

Referring now to Fig. 5, the narrowing line from B to D extends substantially vertically toward the sole, like the line B—D in Fig. 4, but from D to E it is kinked and extends around and below the ankle.

Referring now to Fig. 3 this heel is knit in the manner described with reference to Fig. 2 from $c-c$ to $d-d$ but from $e-e$ to $f-f$ a smaller number of heel loops is narrowed in the manner which is usual at the instep for improving the fit of the heel.

Referring to Fig. 6, the narrowing line extends from B to E in the manner illustrated in Fig. 5 but then it jumps to a point E' near the sole and now extends in the vicinity of the ankle from E' to F.

I wish it to be understood that I do not desire to be limited to the exact details of construction shown and described for obvious modifications will occur to a person skilled in the art.

I claim:

1. The method of knitting stockings in a single operation on flat knitting machines comprising widening the heel by widening of selvedge meshes to be seamed, narrowing heel loops for obtaining the rounding of the heel while skipping the

selvedge loops, and narrowing all heel loops for obtaining the narrowing at the heel.

2. The method of knitting stockings in a single operation on flat knitting machines comprising 5 obtaining the widening of the heel by widening of selvedge meshes to be seamed, narrowing heel loops for obtaining the rounding of the heel, retracting the tickler for one needle per loop while narrowing the heel loops without the selvedge 10 loops for one needle, and retracting the tickler for two needles while narrowing all heel loops for two needles for obtaining the narrowing at the heel.

3. The method of knitting stockings in a single 15 operation on flat knitting machines comprising widening the heel by widening of selvedge meshes to be seamed, narrowing heel loops for obtaining the rounding of the heel while skipping the sel-

vedge loops, and narrowing all heel loops for obtaining the narrowing at the heel for two needles while the tickler is retracted for two needles in the first half of the narrowing stage, and for one needle in the second half.

4. The method of knitting stockings in a single operation on flat knitting machines comprising 80 widening the heel by widening of selvedge meshes to be seamed, narrowing heel loops for obtaining the rounding of the heel while skipping the selvedge loops, narrowing all heel loops for obtaining the narrowing at the heel for two needles while the tickler is retracted for two needles in the first half of the narrowing stage, and for one 85 needle in the second half, and adding several narrowing rows in the manner of instep gussets during said second half.

WOLDEMAR HEINITZ.
